UNITED STATES PATENT OFFICE.

SIMON SNYDER, OF MUNCY, PENNSYLVANIA, ASSIGNOR TO SPROUT, WALDRON & CO., OF MUNCY, PENNSYLVANIA, A CORPORATION OF PENNSYLVANIA.

FEEDING DEVICE.

Original Application filed June 21, 1923, Serial No. 646,964. Divided and this application filed July 13, 1923. Serial No. 651,340.

To all whom it may concern:

Be it known that I, SIMON SNYDER, a citizen of the United States, residing at Muncy, in the county of Lycoming and State 5 of Pennsylvania, have invented certain new and useful Improvements in Feeding Devices; and I do hereby declare the following to be a full, clear, and exact description of the invention, such as will enable others skilled in the art to which it appertains to 10 make and use the same.

This invention relates to devices for use in feeding granular materials such as flour, ground grain, and various feed materials or 15 stock feed of various kinds in measured or predetermined quantities; the device being especially designed and adapted for use in feeding and mixing different kinds of grain or other materials by means of a group of 20 such feeding devices connected in gangs, each device or machine being adapted to deliver a given quantity of material in a given period of time, for admixture with material delivered by another machine or 25 other machines in the group, in the manner illustrated and described in my application, Serial No. 646,964, filed June 21, 1923, for variable speed mechanism for feeders connected in gangs; this application being a 30 division of my aforesaid application.

The objects of the invention are to provide a feeding device of the character referred to having a series of pockets each adapted to hold a given amount or predetermined quantity of material to be discharged therefrom for admixture with other material coming from another or other similar feeding devices, the pockets being so constructed that the filling or loading and discharging or unloading the same in succession is accomplished more effectually and expeditiously than is possible with feeding devices of a somewhat similar character heretofore used for this purpose.

The invention will first be hereinafter more particularly described, with reference to the accompanying drawings, which are to be taken as a part of this specification, and then pointed out in the claims at the end of 45 the description.

In said drawings, Fig. 1 is a vertical sectional elevation of a feeding device embodying my invention;

Fig. 2 is a perspective view of the feed drum detached;

Fig. 3 is a vertical sectional elevation of a modified form of the device;

Fig. 4 is a perspective view of the modified form of feed drum shown in Fig. 3; and

Fig. 5 is a diagrammatic view of another 60 modification.

Referring to said drawings, in which the same reference characters are used to denote corresponding parts in different views, the letter A may denote a casing constructed of 65 wood or metal, preferably metal, having side or end plates a in which suitable bearings are provided for the shaft of a feed drum B rotatably mounted in said casing. The side or end plates a are connected by 70 suitable tie bolts a¹ and between said plates is secured a curved plate a² which extends in a gradual curve from the front upper end of the casing downwardly and thence upwardly to the tie bolt near the rear wall of the casing which forms a support for the rear end of said curved plate, which forms the front wall and bottom of the casing, terminating a sufficient distance from the rear wall of 75 the casing to provide a discharge passage 80 between said tie bolt and rear wall; an open space being provided at the rear of the feed wheel or drum, between its periphery and the rear wall of the casing, extending upwardly from said passage to a point above 85 that at which the pockets begin to discharge their contents, so that said wall may not obstruct or hinder the passage of material through said space. A forwardly and downwardly inclined casing member or 90 plate a³ is also secured between the side plates a so as to form the rear wall of a hopper with an open bottom which discharges into the pockets of the feed drum; said plate a³ terminating a sufficient distance above the plate a² to provide an open space through which the ground or comminuted material is delivered to the pockets of the feed drum. The bearings of the drum

shaft may be of any suitable construction, such as are ordinarily used in milling machines, and therefore need not be specifically described or shown. The feed drum B, as shown in Figs. 1 and 2, consists of a central tubular hub-like member b having rigidly secured thereto or formed integrally therewith between head plates b¹, a series of curved radially extending pocket-forming vanes or flanges b² which are curved in the direction of rotation on the arc of a circle 105 110

that intersects the axis of the drum, so that the concave extremities or outer edges of two oppositely disposed vanes lie in substantially the same vertical or horizontal plane 5 as indicated by the vertical line in Fig. 1 of the drawings, while the base of one of said vanes is arranged at one side of said axis and the base of the other vane on the other side of said axis, with the concave surfaces 10 of the two vanes facing in opposite directions, thus adapting the vanes to scoop up the material as they move toward the hopper and more effectually fill the pockets as the drum rotates than is possible in using feed 15 drums as heretofore ordinarily constructed, or those having straight radial vanes, and as the drum continues to revolve, when the discharge passage of the casing is reached, the convex surface of the next preceding vane 20 in the series forms the bottom of the pocket for the time being and as it is curved downwardly it will begin to discharge the ground or comminuted material before the vane reaches a horizontal plane intersecting the 25 axis of the drum, as indicated by the horizontal line in Fig. 1, and the pocket will be emptied before the outer edge of the vane forming the bottom of the pocket for the time being has reached the rear end of the 30 lower wall or bottom of the casing. But it will be observed that the unloading operation is gradual and continuous, commencing at a point above the axis of the drum and continuing until the outer edge of the 35 blade or vane forming for the time being the bottom of the pocket that is being unloaded has passed considerably below the plane of said axis, thereby effecting a more perfect and uniform admixture of the material delivered by one machine with materials delivered by other machines in the group, each adapted to deliver a given quantity of 40 material in a given period of time, than is possible in using machines of the same type as heretofore constructed and with greater accuracy in regulating the quantity of grain or other material to be measured and delivered by the drum in a given space of time. 45

The peripheral portions or outer edges of 50 the vanes may extend substantially parallel with the drum shaft, as shown in Figs. 1 and 2 of the drawings, or at an angle thereto, as shown in Figs. 3 and 4, the latter form being adapted to facilitate the filling of the 55 pockets and the discharge of the material therefrom, by coming into action at one end and continuing gradually across the length of the drum toward the other end thereof, so that the filling and discharging action of 60 the vanes is spread over a larger surface than with vanes which extend parallel with the shaft, and the stock is left in better condition for commingling with other grain or material discharged from other machines 65 in the group.

In the modification shown in Figs. 3 and 4 the feed drum is formed with concentric tubular members b^3 and b^4 , the inner one of which receives the drum shaft while the outer one has formed integrally therewith 70 a series of pocket-forming vanes or flanges b^5 which are curved upon the arc of a circle as in the construction before described, so that a line indicating a continuation of the curve will intersect the axis of the drum, as 75 indicated in Fig. 3 of the drawings.

When used in a group, each machine may be provided with a spout emptying into the casing mouth or hopper, and with a discharge spout leading to a common outlet, for 80 commingling or mixing the stock as it is discharged from the group of machines, or each machine may be provided with a separate discharge spout for conducting the stock into separate receptacles, as may be desired 85 in practical use.

Fig. 5 is a diagrammatic illustration of a construction in which there are a multiplicity of pocket-forming vanes, each of which is formed upon the arc of a circle intersecting the axis of the drum, for feeding finely comminuted materials, the operation of loading and unloading or filling and discharging being substantially the same as hereinbefore explained with reference to the 90 lesser number of pockets shown in Figs. 1 to 4 of the drawings.

Having thus described my invention, what I claim as new and desire to secure by Letters Patent of the United States is:—

1. In a machine of the character described, a feed drum rotatably mounted in a casing having a feed hopper arranged to deliver material to the drum in front thereof, the front wall of said hopper being extended in a gentle curve downwardly and rearwardly and thence upwardly to a point at the rear of the drum near the rear wall of the casing and curved to conform to the curvature of the peripheral portion of the drum; an open space being provided between the periphery of the drum and the rear wall of the casing extending from a point considerably above the axis of the drum to the lower end of the casing, said drum being constructed with a hub-like central portion having a series of uniformly spaced pocket-forming blades or vanes projecting from said central portion in curved lines each struck upon substantially the arc of a circle intersecting said central portion at a point diametrically opposite the point at which another vane is joined thereto and having its concave surface facing the convex surface of the next preceding vane in the series, in the direction of rotation of the drum, whereby the vanes are adapted to operate with a scoop-like action in filling the pockets and to effect a gradual discharge of the contents of 125

the pockets commencing at a point above the horizontal axis of the drum and continuing until the outer edge of the blade or vane forming the bottom of the pocket that is being emptied has passed considerably below said axis substantially as described.

2. In a machine of the character described, a feed drum rotatably mounted in a casing having a feed hopper arranged to deliver material to the drum in front thereof, the front wall of said hopper being extended in a gentle curve downwardly and rearwardly and thence upwardly to a point at the rear of the drum near the rear wall of the casing and curved to conform to the curvature of the peripheral portion of the drum; an open space being provided between the periphery of the drum and the rear wall of the casing extending from a point considerably above the axis of the drum to the lower end of the casing, said drum being constructed with a hub-like central portion having a series of uniformly spaced pocket-forming blades or vanes projecting from said central portion in curved lines each struck upon substantially the arc of a circle intersecting said central portion at a point diametrically opposite the point at which another vane is joined thereto and having its concave surface facing the convex surface of the next preceding vane in the series, in the direction of rotation of the drum, whereby the vanes are adapted to operate with a scoop-like action in filling the pockets and to effect a gradual discharge of the contents of the pockets commencing at a point above the horizontal axis of the drum and continuing until the outer edge of the blade or vane forming the bottom of the pocket that is being emptied has passed considerably below said axis, said vanes extending lengthwise of the drum at an angle to its axis so as to adapt them to come into action at one end and continue gradually across the length of the drum toward the other end thereof, so that the filling and discharging action of the vanes is extended over a larger surface than with vanes which

extend parallel with the shaft, substantially as described.

3. A machine for feeding granular material in measured or predetermined quantities, comprising a casing having a feed hopper at the upper front end thereof and a discharge passage at its lower rear end, and a feed drum revolvably mounted in said casing having a series of uniformly spaced pocket-forming blades or vanes which project from the axis of the drum in curved lines each struck upon substantially the arc of a circle intersecting said axis at a point diametrically opposite the junction therewith of another vane and having its concave surface facing the convex surface of the next preceding vane in the series, in the direction of rotation of the drum; the front wall of said hopper being extended in a gentle curve downwardly and rearwardly and thence upwardly to a point in substantially the same vertical plane as the free edges of said vanes at the rear of the drum and forming a hopper bottom of substantially the same curvature as the peripheral portion of the drum; an open space being provided between the periphery of the drum and the rear wall of the casing extending from a point considerably above the axis of the drum to said discharge passage, the mouth of said hopper and said passage being located on opposite sides of the drum in a plane extending diagonally across said casing from the upper front end thereof to its lower rear end substantially midway of the drum; said vanes being adapted to scoop up the material at the delivery end of the hopper and to gradually discharge the same commencing at a point above the horizontal axis of the drum and continuing until the outer edge of the blade or vane forming the bottom of the pocket that is being emptied has passed considerably below said axis.

In testimony whereof I affix my signature in the presence of two witnesses.

SIMON SNYDER.
